Primary Examiner — Kevin K Rudzinski*Assistant Examiner* — Amber J Rabie(74) *Attorney, Agent, or Firm* — Suzanne Kikel, Patent Agent(57) **CLAIM**

The ornamental design for a shirt with shoulder pockets, as shown and described.

DESCRIPTION

FIG. 1 is a right side, front perspective view of a shirt with shoulder pockets, showing my new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view thereof.

The broken line showing of a shirt in the figures represents portions of the article and forms no part of the claimed design. The broken lines along the three outer edges of the pockets on each shoulder represent stitching and forms part of the claim.
